UNITED STATES PATENT OFFICE.

JAMES E. McBETH, OF NEW ORLEANS, LOUISIANA.

IMPROVEMENT IN THIMBLES.

Specification forming part of Letters Patent No. **80,755**, dated August 4, 1868.

To all whom it may concern:

Be it known that I, JAMES E. McBETH, of New Orleans, in the parish of Orleans, and in the State of Louisiana, have invented a certain new and useful Improvement in Thimbles; and do hereby declare that the following is a full, clear, and exact description thereof, reference being had to the accompanying drawings, and to the letters of reference marked thereon.

My invention consists in constructing a thimble in such a manner that less material is used in the formation; that the finger is not injured by the use thereof, and to prevent the perspiration of the finger. The main portion of my thimble is provided with a series of openings, of any desired shape, and at the lower end of which is a circumferential rim, which is directly above the usual needle indentations.

In order to enable others skilled in the art to make and use my invention, I will now proceed to describe its construction and operation, referring to the annexed drawings, which form a part of this specification.

A represents the cap of a thimble, made in any of the known and usual ways, to which the body B is attached, or the cap and body may be made in one piece. A rim or ring, a,

is placed around the body B at the point where the cap commences, which prevents the head of the needle slipping down below said rim.

The body B is cut with a series of holes, extending all around the same, and from the rim *a* to near the lower edge. These holes may be of any number and shape desired.

It will be seen that when the finger is inserted in a thimble thus constructed, the flesh will protrude through these openings, and effectually prevent the thimble from falling off. Besides, it presents a neater appearance, and is considerably lighter than the ordinary thimble.

Having thus fully described my invention, what I claim as new, and desire to secure by Letters Patent, is—

A thimble, whose body is provided with a series of openings, at the lower end of which is a circumferential projecting rim, *a*, and whose lower part, A, is suitably indented, all as herein shown and described.

In testimony that I claim the foregoing I have hereunto set my hand this 18th day of July, 1868.

JAMES E. McBETH.
